(57) **CLAIM**

The ornamental design for a bracelet, as shown and described.

DESCRIPTION

1. Bracelet
2. Bracelet
- 1.1 : Perspective
- 1.2 : Left
- 1.3 : Top
- 1.4 : Bottom
- 1.5 : Perspective
- 1.6 : Left
- 1.7 : Top
- 1.8 : Bottom
- 2.1 : Perspective
- 2.2 : Left
- 2.3 : Top
- 2.4 : Bottom
- 2.5 : Perspective
- 2.6 : Left
- 2.7 : Top
- 2.8 : Bottom

The design lies in the shape and configuration of the article shown in the drawings; features shown in even broken lines do not form part of the claimed design, and are shown for context only; radial lines illustrate light radiating from the article.

1 Claim, 16 Drawing Sheets
